UNITED STATES PATENT OFFICE.

WILLIE JOHN BOEMPER, OF NEW YORK, N. Y., ASSIGNOR OF ONE-HALF TO
AARON HERZBERG, OF NEW YORK, N. Y.

MOTOR.

SPECIFICATION forming part of Letters Patent No. 729,995, dated June 2, 1903.

Application filed April 18, 1902. Serial No. 103,480. (No model.)

To all whom it may concern:

Be it known that I, WILLIE JOHN BOEMPER, a citizen of the United States, and a resident of New York city, borough of Manhattan, State 5 of New York, have invented certain new and useful Improvements in Motors, of which the following is a specification.

The object of my invention is to provide a simple and efficient motor capable of being 10 operated by gas from the gas-mains in a house or other building and adapted to operate a rotary fan for cooling the air in rooms, &c.; and to this end my invention comprises the novel 15 details of improvement that will be more fully hereinafter set forth and then pointed out in the claims.

Reference is to be had to the accompanying drawings, forming part hereof, wherein—

Figure 1 is a side elevation of a fan-motor 20 embodying my invention. Fig. 2 is a face view thereof. Fig. 3 is an enlarged vertical cross-section through the casing substantially on the line *x* *x* in Fig. 4. Fig. 4 is a view at right angles to Fig. 3, part of the casing being removed, as indicated by the line 4-4 in Fig. 3. Fig. 5 is an enlarged detail vertical section of the motor-cylinder and parts connected therewith. Fig. 6 is a horizontal section on the plane of the line *y* *y* in Fig. 5. 25 Fig. 7 is an enlarged detail view of part of the gearing operated by the motor-piston, and Fig. 8 is a section on the line *z* *z* in Fig. 7.

Similar numerals of reference indicate corresponding parts in the several views.

In the drawings the numeral 1 indicates a 35 suitable casing or frame adapted to contain the operative parts of my improved motor, said casing being shown provided with a door or cover 1^a to permit access to the interior 40 thereof.

2 indicates a cylinder shown supported within the casing 1 as by a bracket 3 or in other suitable manner, and from the piston 4 the piston-rod 4^a 4^b extends through suitable 45 stuffing-boxes at opposite ends of the cylinder. Said cylinder is provided with exhaust-ports and valves, (indicated at 5 5^a.) Gas-inlet pipes 6 7 connect with the cylinder 2 near opposite ends thereof, and in the example shown 50 said pipes connect with a pipe 8, which communicates with a two-way cock 9, that is

adapted to be connected with a gas-main in any suitable manner. The pipes 6 and 7 are provided with apertures to permit a mixture of gas and air to pass into cylinder 2. 55

The means I have shown for regulating the amount of air that is to be mixed with the gas in the pipes 6 7 comprises sleeves 10 11, mounted to slide on said pipes, so as to cover said apertures more or less, and said sleeves 60 are shown connected by a bar 12, adapted to be adjusted along said pipes as by means of a screw 13, supported by casing 1, whereby as said screw is rotated the sleeves 10 11 will be adjusted to uncover the apertures in pipes 65 6 7 more or less, as required.

14 15 indicate valves located in the pipes 6 7 and normally held on their seats by springs, such valves being arranged to prevent back pressure from the cylinder 2 from passing 70 into the pipes 6 7.

The means I have shown for igniting the explosive charges in the cylinder 2 comprise a tube 16, connected with the two-way cock 9 and having a valve 17 to independently control the flow of gas through said pipe, and said pipe has gas jets or tips 16^a 16^b, located adjacent to but at a suitable distance from ports or apertures 2^a 2^b near opposite ends of the cylinder 2. (See Figs. 3 and 6.) The 80 ports 2^a 2^b are controlled by slides 18 19, connected with the piston-rod 4^a 4^b, respectively, and adapted to slide in contact with a suitable face or bearing 2^c on the cylinder 2, the slides 18 19 being so arranged that 85 when the piston is at the end of a stroke one of the ports 2^a or 2^b will be opened, while the other is closed. The slides 18 19 reciprocate with the piston for controlling the back pressure in the cylinder. To further assist in 90 preventing the pressure from entering the pipes 6 and 7, the piston 4 may be provided with a shield 4^c, adapted to fit snugly within the cylinder, (see Figs. 5 and 6,) said shield being of such dimension that when the piston 95 4 is at the end of a stroke the appropriate end of the slide which projects from opposite sides of said cylinder will cover the inner end of the pipe 6 or 7, as the case may be. It will be observed that after the piston 4 moves a short distance from its extreme outward position the slide 4^c will uncover the 100

outlet of pipe 6 or 7 to permit the gas-and-air mixture to enter the cylinder, and the slide will only close such pipe when the piston arrives near the end of its stroke.

5 20 indicates a rotary fan, which may be of suitable construction, and the same is shown carried by a shaft 21, journaled in suitable bearings supported by the casing 1, said shaft being operated by said motor. In the construction I have shown for operating the fan by the motor the shaft 21 has secured to it a ratchet-wheel 22, which is surrounded by a pinion or gear-wheel 23, adapted to rotate freely independently of the ratchet-wheel 22 in one direction, but adapted to cause said ratchet-wheel and the shaft 21 to rotate in the opposite direction, the connection between the wheel 22 and pinion 23 being shown consisting of pins or rods 24, carried in bearings 20 in said pinion and projecting into the path of the ratchet-teeth, being normally pressed toward said ratchet by springs 24^a. (See Figs. 7 and 8.) One or more of such pins and springs can be used, if desired. One face of 25 the ratchet-teeth is inclined or beveled, and the opposite face is radial, so that when the pinion 23 is rotated in the direction of the arrow in Fig. 7 the pin 24 will cause ratchet 22 and shaft 21 to rotate in the same direction, 30 and when pinion 23 is rotated in the reverse direction the dog or pin 24 will slip over the ratchet-teeth. The pinion 23 gears or meshes with a rack 25, connected with the piston-rod 4^a. It will thus be seen that the piston 4 will 35 impart intermittent motion to the shaft 21 by the device described. In order to cause the piston 4 to impart motion to shaft 21 at each stroke, I provide the piston-rod 4^b with a rack 26, that meshes with a pinion 27, that surrounds a ratchet 28, supported by a shaft 29, 40 suitably carried by casing 1, said pinion and ratchet being provided with a dog or pin and spring similar to 24 24^a, the ratchet, however, being reversed in position relatively to the 45 position of the ratchet 22, so that when the piston moves upwardly, as illustrated in the drawings, the pinion and ratchet 23 24 will rotate the shaft 21 in the direction of the arrow in Fig. 7, pinion 27 running idle, and on 50 the return stroke of the piston rack 26 and pinion 27 will rotate ratchet 28 in the reverse direction, pinion 23 running idle. The ratchet 28 is connected with a pinion 30, that 55 meshes with an idler 31, journaled on a shaft 32, carried by the casing 1, the gear 31 meshing with a pinion 33, secured on shaft 21, whereby as rack 26 descends the gearing described will cause shaft 21 to rotate in the same 60 direction as it is rotated by pinion 23. Thus as the piston reciprocates a continuous rotary motion in one direction is imparted to shaft 21 and its fan.

The operation of my improvements may be 65 described as follows: In starting the motor the two-way cock 9 is first turned so as to admit the gas to pipe 16, and cock 17 being turned

the jets at 16^a 16^b are lighted. The cock 9 is then further turned to admit gas to pipe 8, and the desired amount of air is mixed with 70 the gas in the pipes 6 and 7. The motor is then started, and as piston 4 descends from the position shown in Fig. 5 an explosive mixture will be drawn into the upper end of the cylinder, and on the return stroke of the piston this mixture will be compressed, and at 75 the same time a charge will be drawn into the lower end of the cylinder. When the piston moves upwardly so far that the shield 18 uncovers the port 2^a, the compressed mixture will issue from said opening and will be ignited by the flame 16^a, and thereupon an explosion will occur within the cylinder, forcing back the piston and compressing the charge 80 in the part of the cylinder beneath the same, 85 and the shield 19 will at the proper moment uncover the port 2^b to permit the charge to ignite at the jet 16^b, and so on as the piston reciprocates, it being understood that after 90 the explosion has taken place at each end of the cylinder the latter is exhausted on the corresponding return stroke of the piston. It will be apparent that the motor operates on the four-cycle type, and that as the same operation occurs on each side of the piston 95 there will result an explosion for each two strokes of the piston. At each stroke of the piston motion is imparted to the shaft 21, so that a continuous rapid rotation of fan 20 can be effected. Of course the shaft 21 can be 100 utilized to transmit power to other devices than to the fan in any desired manner.

My invention is not limited to the details of construction and arrangements shown and described, as they may be varied without departing from the spirit thereof.

Having now described my invention, what I claim is—

1. The combination of a cylinder, a piston, a pair of perforated mixing-chambers leading 110 to the cylinder near opposite ends, sleeves mounted on said chambers to regulate the flow of air to said chambers, a bar connecting said sleeves, means to adjust said bar and sleeves, and means to ignite charges in said 115 cylinder, substantially as described.

2. The combination of a cylinder and piston, rods extending through the ends of said cylinder from opposite sides of said piston, pipes leading to said cylinder near opposite 120 ends, means to prevent back pressure through said pipes, ports opening through said cylinder near opposite ends, shields carried by said rods to control said ports, and a pipe having 125 gas jets or tips adjacent to said ports exterior of the cylinder, substantially as described.

3. The combination of a cylinder and piston, with a pair of pipes leading to the cylinder near opposite ends thereof, a feed-pipe connected with said pipes, a two-way cock 130 connected with the feed-pipe, a pipe 16 connected with said cock and provided with jets, ports opening through said cylinder near opposite ends adjacent to said jets, said piston

having rods extending through opposite ends of the cylinder, slides connected with said rods adapted to bear on guides on the exterior of the cylinder to control said ports, and means to prevent back pressure through the cylinder from said pipes, substantially as described.

4. The combination of a cylinder and piston, with a pair of pipes leading to the cylinder near opposite ends thereof, a feed-pipe connected with said pipes, a two-way cock connected with the feed-pipe, a pipe 16 connected with said cock and provided with jets, ports opening through said cylinder near opposite ends adjacent to said jets, said piston

having rods extending through opposite ends of the cylinder, slides connected with said rods adapted to bear on guides on the exterior of the cylinder to control said ports, and means to prevent back pressure through the cylinder from said pipes, said piston having a shield extending from opposite ends thereof and bearing against the inner wall of the cylinder adapted to open and close the inlet of said pipes in the cylinder, substantially as described.

WILLIE JOHN BOEMPER.
